UNITED STATES PATENT OFFICE

WALTER RAWLING, JAMES MARSHALL, AND JOHN BAKER RUMFORD, OF CESSNOCK,
AUSTRALIA

APPARATUS FOR TIPPING TRAVELING MINE SKIPS

Application filed August 31, 1928, Serial No. 303,340, and in Australia September 1, 1927.

This invention relates to the emptying of traveling mine-skips and the like by inverting them so that their contents fall out, and the object of the invention is to provide simple means whereby a skip without being stopped is turned over endwise, returned upon its previous course, restored to normal position and propelled from the apparatus in continuation of its course.

10 The invention consists in apparatus comprising a continuous rail track arranged in open loop formation in a substantially vertical plane, and for portion of its length composed of rails of channel section with their 15 channels opposed, and angle irons, and an endless mechanically operated creeper chain equipped with fingers to engage the axles of the skips and carry the latter around the loop substantially as hereinafter described and 20 shown in the accompanying drawings. The invention also consists in certain other features as hereinafter ascertained.

Reference is now made to the accompanying diagrammatic drawings which depict an 25 embodiment of the invention and in which,

Fig. 1 is a perspective view of the apparatus in which the looped rail track is constituted in part by rails of channel section and in part by rails of angle section;

30 Fig. 2 is a side elevation of the apparatus showing a number of skips in various positions thereon;

Fig. 3 is a fragmentary sectional plan view 35 showing chain guides for directing the chains on and off sprockets at the entry and exit ends respectively of the loop; and

Fig. 4 is a fragmentary sectional plan view 40 showing chain guides for directing the chains on and off sprockets which are mounted concentrically with the curved portions of the track.

Referring to Figs. 1 and 2, 1 represents the rails of the ordinary track from which the skips enter the apparatus. The entry section of the loop track is constituted by rails 2 which register with the rails 1, and has a slight upward inclination as clearly shown in Fig. 2, for the purpose of steadyng the skips and preventing them from overrunning. The entry section of the track regis-

ters with and merges into a downwardly and rearwardly curved section constituted by two curved channel rails 3 disposed with their channels opposed and which are of a size to freely accommodate the wheels of the skips. 55

From the lower end of this curved section, hereinafter referred to as the first curved section, a central or return section of the track, composed of angle iron rails 4, extends rearwardly and horizontally in a direction slightly oblique to the direction of the entry section, said central section terminally registering with an upwardly and forwardly curved section constituted by two curved channel rails 5 similar and arranged 60 similarly to the channel rails 3. This upwardly and forwardly curved section is hereinafter referred to as the second curved section. 65

The upper ends of the channel rails 5 respectively register with and lead on to a pair of rails 6 constituting the exit section of the track; this section has a slight downward inclination as clearly shown in Fig. 2, and leads in a direction to avoid the first curved 70 section and to join a lead off track 7.

Concentric with the channel rails 3 of the first curved section and arranged midway between them is a sprocket wheel 8 on a shaft 9 rotatably mounted in cross bars such as 80 10, and a similar and similarly arranged and mounted sprocket wheel 11 is concentric with the channel rails 5 of the second curved section.

A smaller sprocket wheel 12 is mounted at 85 the outer end of the entry section of the track between the rails 2 in brackets 13 attached to the rails 2, and a similar sprocket wheel 14 is similarly mounted between the rails 6 at the outer end of the exit section of the 90 track. Reeved about these sprockets 8, 11, 12 and 14 is an endless chain 15 arranged in the manner shown and equipped at intervals with rigid fingers 16. Power from any appropriate source is applied per medium of 95 belt pulley 17 mounted on the axle of sprocket 12, to impart motion to the chain in the direction indicated by the arrows; and the respective diameters and the arrangement of the sprockets is such that portions of the 100

chain are maintained parallel with the straight sections and concentric with the curved sections of the track at all times, while the length of the fingers 16 is sufficient to enable them to engage the axles of the wheels 18 of skips 19 while the latter are traversing the loop track as hereinafter explained.

It will be observed that the lead of chain 15 from sprocket 14 and on to sprocket 12 is 10 slightly angular. To eliminate any tendency of the chain to jamb, and to diminish wear and tear of the sprockets and chain, we provide guides such as 20 and 21 (see Fig. 3) to guide the chain off and on sprockets 14 and 15 12 respectively.

For the same reason guides 22 and 23 (see Fig. 4) are provided to guide the chain off and on the sprockets 8 and 11 respectively.

The operation is as follows:—

20 A loaded skip entering the entry section from the track rails 1 on to the rails 2, has one of its axles engaged by one of the fingers 16 of the moving chain 15 which drags the skip up the incline to the first curved section 25 where the wheels 18 enter the channel rails 3 and pass around the downward curvature of the track at this end, the skip in its passage being inverted so that its contents fall out as shown at 24 (Fig. 2). The empty and inverted skip suspended from its wheels, now enters the central section of the track, and is propelled thereon by the chain fingers 16 towards the second curved section of the track, the wheels rolling on the horizontal portions 35 of the angle irons 4. Having traveled along the central section, the skip wheels enter the channel rails 5 of the second curved section, the skip is forced upwardly around this curved portion of the track, and is thereby 40 restored to its upright position. From the channel rails 5 the skip enters the exit section of the track and while on the downward incline thereof, its progress along the rails 6 is controlled by the engagement of one of 45 its axles with one of the fingers 16 until, at the point where the chain curves downwardly about the sprocket 14 and recedes from the track level, the skip is released and gravitates on to the lead off section 7 of the track.

50 What we claim and desire to secure by Letters Patent is:—

1. Apparatus for tipping traveling mine-skips comprising a continuous rail track consisting of an upwardly inclined entry section, 55 a downwardly and rearwardly curved section joined at its upper end to the forward end of the entry section and composed of rails of channel section with the channels opposed, a central or return section joined at one end 60 to the lower end of said curved section, and upwardly and forwardly curved section joined at its lower end to the other end of the central section and composed of channel rails with their channels opposed, said central section being at a slight angle, horizon-

tally, to the entry section, and an exit section joined at one end to the upper end of the last mentioned curved section; and, in combination with said track, means for progressing a mine-skip about said track, said means comprising an endless chain equipped with fingers to engage an element of the under frame of a skip on the track, and four sprockets, one of which is power driven, about which said chain is reeved, two of said sprockets being located respectively at the entry and exit ends of the track, while the other two respectively are mounted concentrically with the curved portions of the track; all operating as and for the purpose set forth. 70

2. Apparatus according to claim 1 including a chain guide located adjacent each sprocket to or from which the lead of the chain is angular to the plane of revolution of the sprocket, for the purpose set forth. 75

Signed at Cessnock, New South Wales, this thirtieth day of July, A. D. 1928.
